UNITED STATES PATENT OFFICE.

HARRY E. SAFFORD, OF ALLEGHENY, PENNSYLVANIA.

FIRE-EXTINGUISHER.

SPECIFICATION forming part of Letters Patent No. 439,565, dated October 28, 1890.

Application filed June 4, 1890. Serial No. 354,205. (No model.)

To all whom it may concern:

Be it known that I, HARRY E. SAFFORD, a resident of Allegheny, in the county of Allegheny and State of Pennsylvania, have invented a new and useful Improvement in Fire-Extinguishers; and I do hereby declare the following to be a full, clear, and exact description thereof.

My invention relates to fire-extinguishers, and more especially to that class of extinguishers in which the fluid is contained within a suitable reservoir and is expelled therefrom, when needed, by compressed air confined within said reservoir, or by a pump. 15 should the volume of compressed air fail. This style of fire-extinguisher is well adapted for use in hotels or large public buildings, where such apparatus may be brought into service on a moment's notice. Hence the necessity of its always being in perfect working order. The most prevalent defect, perhaps, encountered in the use of this form of extinguisher is due to the uncertainty of being able to unseat the valve at the lower 20 end of the pump to allow the fluid within the reservoir to ascend the pump and be discharged at the outlet thereof. This difficulty of unseating the valve is attributed to the action of the fluid, which, being in contact 25 with said valve, corrodes the metal and causes the valve to adhere to its seat, for the extinguisher may remain idle for a year or more, during which time there is ample opportunity for this corrosive action to take place.

30 The object of my invention, therefore, is to remove this objection; and it consists, generally stated, in a reservoir or tank having a pump attached thereto, the piston of said pump being adapted to engage with the lower 35 valve of the pump and turn the same on its seat, so that upon turning the piston slightly the said lower valve will be unseated and allowed to rise as the piston ascends within the pump-cylinder.

40 To enable others skilled in the art to make and use my invention, I will describe the same more fully, referring to the accompanying drawings, in which—

Figure 1 is a side view, partly in section, 45 of my improved apparatus. Fig. 2 is an enlarged view of the piston about to engage with the lower valve. Fig. 3 is a like view

showing the manner of engagement. Fig. 4 is an enlarged detail top view of the lower valve. Fig. 5 is a modification thereof. Fig. 55 5 is a view showing the locking device out of engagement.

Like letters indicate like parts.

The fluid reservoir or tank *a* may be of any convenient size or shape, and is constructed 60 of copper or other suitable metal. An opening *a'* is formed in the head of the reservoir *a*, and within said opening is inserted the casing *b*, said casing to extend within the reservoir *a* to a point below the "fluid-line," 65 and is constructed of any suitable metal.

To secure the casing *b* within the reservoir *a*, I first solder or otherwise securely attach the upper end of the casing *b* to the ring or collar *b'*, said ring or collar exactly fitting 70 within the opening *a'* and soldered thereto to form a very rigid connection, and to further strengthen this connection I seal the space around the inner face of said ring *b'* with the lead, as at *b*². This serves to render 75 the connection of the casing with the reservoir practically air-tight, the importance of which will more fully hereinafter appear. Any other manner of securing the casing *b* which will produce a like result may, however, be employed. Supported by the casing 80 *b*, and fitting close to the ring *b'*, is the inferiorly-threaded collar *c*, with which the cylinder *d* of the pump *D* is adapted to engage.

The general construction of the pump *D* is 85 similar to any of the well-known forms of hand-pumps, said pump having the pump-cylinder *d*, the air-chamber *d'*, and the outlet-port *d*², having the hose-connection *d*³. A piston-rod *e*, having the handle *e'* thereon, passes 90 down through a suitable stuffing-box *f*, through the air-chamber *d'* into the cylinder *d*, and has secured thereto the piston *e*². The piston *e*² is hollow, having the passage *e*³, through which the fluid passes during the 95 downstroke, said piston being provided with the ordinary valve *g*, resting in the valve-seat *g'* at the upper end of the passage *e*³, said valve rising as the hollow piston *e*² descends, and seating itself again when said piston rises. The openings *g*², formed in the piston-rod *e*, just beyond the piston *e*², permits 100 the rising fluid to escape to the cylinder of the pump. The piston *e*² has the teeth or

projection h formed on the lower end thereof, said teeth being adapted to engage with the interdental spaces i' , formed by the serrated face i on the upper face of the valve 5 j , so forming a clutch-connection with said valve. The valve j is seated in the valve-seat j' in the extension k of the cylinder d , and said valve j must ascend when the hollow piston e^2 ascends before the fluid in the 10 supply-reservoir can escape to the pump-cylinder to be discharged through the outlet-port d^2 . It is this valve j which, through the corrosive action of the fluid adheres tightly to the valve-seat j' , and it is very apparent 15 that unless said valve is unseated on first raising the hollow piston e^2 , the next movement of said piston being downward, will only serve to increase the power of resistance of said valve j to the volume of water below it. Any 20 other suitable form of clutch may be employed to bring about this engagement of the piston e^2 with the valve j , a modified form being shown in Fig. 5. The advantages of the clutching device shown and described, 25 however, lie in the fact that whatever be the position of the teeth h relative to the interdental spaces i' of the serrated face i upon the descent of the piston e^2 , and although the said teeth h may not exactly coincide with 30 said spaces i' , yet upon the further descent of said piston the edges of the teeth h are sure to strike the inclined faces of the teeth of the serrated face i , and descending thereon will finally fit within the spaces i' . A 35 very sure manner of guiding the teeth h into engagement with the spaces i' is thus afforded. A slight turn of the piston-rod e when such connection between the piston e^2 and the valve j is made will suffice to unseat 40 said valve to allow the water to rise through it to the pump-cylinder. To provide for this turning of the piston-rod e , said piston-rod is furnished with the cross-pin l at a point just beyond the stuffing-box f , while said stuffing- 45 box is formed with the inclined slot m therein, so that by forcing down the piston-rod e , and at the same time turning it slightly, the cross-pin l may be brought to a position where upon forcing said piston-rod down a little farther the 50 cross-pin l is brought to engage with the inclined slot m . In this way the teeth h of the piston e^2 are brought to engage with the teeth of the serrated face i of the valve j , and thus hold the valve to its seat. Instead of a cross-bar and 55 inclined slot, any suitably-threaded or similarly-formed connection may be employed to force the piston against the valve j and hold it in place, which will permit the piston to turn when opened and so through the clutch 60 to turn the valve. A second opening n is formed in the top of the supply-reservoir a for the introduction of the air or fluid, and within said opening is secured the tube o , extending below the fluid-line. A check-valve 65 p is encased within the valve-chamber o^2 at the upper end of the tube o , said valve p having the spring p' interposed between the head

of said valve and the shoulder o' of the valve-chamber o^2 to hold said valve normally in its seat. To further secure the opening n against 70 leakage, it is provided with the cap q , having a small vent q' , which acts to admit air when the pump is used to discharge the fluid by unscrewing said cap to bring the said air-inlet beyond the top of the casing o . 75

The operation of my improved extinguisher is as follows: The tank a is first charged with the fluid until said fluid reaches the fluid-line or a point above the ends of the casing b and of the tube m . An air-pump is adjusted 80 to the opening n , the cap q having been removed, and air is pumped into said opening, forcing down the check-valve p and allowing the air to pass down through the tube o and up through the fluid to the space above the 85 fluid-line. When the required pressure of air within the reservoir has been obtained, the air-pump is removed, when the check-valve p will resume its seat to prevent the escape 90 of the fluid, and the cap q is adjusted to place. 95 It will be observed that by extending the casing b and the tube o to a point below the fluid-line that there is no possibility of the air confined in the space above the fluid escaping through the joints at the openings a' and n , as 100 it would have to pass down through the fluid and up the said casing b and tube o ; but these are also filled with fluid, so that any connections made with the reservoir are fluid-joints—that is, joints to prevent the escape of fluid, 105 and not to prevent the escape of the air, which is practically impossible to do. The piston-rod e is brought to the position shown in Fig. 1 by being forced down and turned until the cross-pin l is in position to enter the slot m in 110 the stuffing-box f , and on turning the said piston-rod e the pin l travels down the inclined slot m and so forces the teeth h at the base of said piston-rod into engagement with the serrated face i of the valve j . The extinguisher is now ready for use at any moment, 115 and if it lies idle for some time the fluid corrodes the valve so that it adheres tightly to its seat. If, now, it is desired to use the extinguisher, the piston-rod e being in the position shown in Fig. 1, the said piston-rod is given a quick turn by means of the handle to bring the cross-pin l to the entrance of the inclined slot m , when the piston-rod e may assume its 120 normal position. This turning of the piston-rod e , with the teeth h in engagement with the serrated face i of the valve j , will cause said valve to turn in its seat and so free said valve from the binding action caused by the corrosion of the fluid and permit the compressed 125 air above the fluid-line to force the fluid up through the valve j to the tube d , and thence to the outlet-port d^2 . The pump D is always in readiness to be employed in case the pressure of the air within the reservoir is not sufficient to discharge the fluid with force enough 130 to carry it the distance desired. In case the pump D is used the cap q must be unscrewed until the vent q' is beyond the top of the cas-

ing *o*, when the said pump may be operated in the ordinary way by means of the handle *e'*.

In my improved extinguisher the pump may be dispensed with entirely by employing simply a tube with a valve therein and a rod engaging with said valve and adapted to hold the valve and turn it in its seat, the compressed air serving to force the liquid to the discharge-port.

10 What I claim as my invention, and desire to secure by Letters Patent, is—

1. In a fire-extinguisher, the combination of a tank having a valve in the escape-tube thereof, a valve-controlling rod, and means whereby the rod is locked to hold the valve upon its seat and released to open the valve, said rod being connected with the valve by a clutch-connection, whereby upon operating the rod to release the valve the latter will be moved 15 upon its seat, substantially as and for the purposes described.

2. In a fire-extinguisher, the combination of a tank having a valve in the escape-tube there-

of, a controlling-rod, and means whereby the rod is locked to hold the valve upon its seat 25 and released to open the valve, said rod having a clutch-connection with the valve, whereby upon operating the rod to release the valve the latter is turned upon its seat, as and for the purpose described.

3. In a fire-extinguisher, the combination of a tank having a valve in the escape-tube thereof, a controlling-rod, and means whereby the rod is locked to hold the valve upon its seat and released to open the valve, said rod having 30 V-shaped teeth thereon engaging with similarly-shaped spaces formed on the valve, whereby upon operating the rod to release the valve the latter is turned upon its seat, substantially as and for the purposes set forth. 40

In testimony whereof I, the said HARRY E. SAFFORD, have hereunto set my hand.

HARRY E. SAFFORD.
